United States Patent

Des. 236,619
Patented Sept. 2, 1975

236,619

BATHTUB

David Harman Powell, 41 High St.,
Malden, Essex, England

Filed May 28, 1974, Ser. No. 474,087

Claims priority, application Great Britain Nov. 27, 1973

Term of patent 14 years

Int. Cl. D23—02

U.S. Cl. D23—55

FIG. 1.

FIG. 2.

FIG. 3.

FIG. 1 is a perspective view taken from the top, one side and end of a bathtub showing my new design;

FIG. 2 is a perspective view taken from the bottom, side and end opposite those shown in FIG. 1; and

FIG. 3 is a cross sectional view taken on line III—III of FIG. 1.

I claim:

The ornamental design for a bathtub, as shown.
